CIRCUIT-INTERRUPTER.

1,189,276.

Specification of Letters Patent.

Patented July 4, 1916.

Application filed September 28, 1912. Serial No. 722,933.

To all whom it may concern:

Be it known that we, JOSEPH N. MAHONEY, and WALTER M. AUSTIN, citizens of the United States, and residents, respectively, of 5 Wilkinsburg and Swissvale, both in the county of Allegheny and State of Pennsylvania, have invented a new and useful Improvement in Circuit-Interrupters, of which the following is a specification.

10 Our invention relates to circuit interrupters and it has special reference to interrupters of the so-called "carbon break" type.

One of the objects of our invention is to provide a device of the above indicated character that shall be simple and durable in construction, effective and reliable in operation and that shall embody coöperating main contact members and a plurality of sets of auxiliary contact terminals to be disengaged 15 successively during the opening operation of the interrupter in order that the final interruption of the circuit shall be confined to the carbon arcing terminals.

Another object of our invention is to provide a circuit interrupter in which the carbon contact terminals are so constructed and arranged, with respect to the main contact members and other auxiliary contact terminals, as to be maintained in coöperative engagement during a portion of the opening 20 operation of the interrupter to permit the separation of the other coöperating contact members and terminals to a sufficient degree to obviate the possibility of reëstablishing 25 the circuit through an arc which might be formed when the interrupter is finally opened.

Another object is to make provision for effecting a sliding or wiping action between 30 the carbon terminals so that they may be kept free from dirt and a good electrical contact may be secured, and a further object is to mount the carbon terminals so that they will be self-aligning.

45 A still further object of our invention is to provide the auxiliary carbon arcing terminals with conducting plates which are adapted to coöperatively engage one another and which are electrically connected to the main 50 contact terminals by means of flexible contact members, thereby insuring a connection of relatively good electrical conductivity in shunt to the main contact members.

A still further object of our invention is

to provide a set of intermediate auxiliary 55 contact terminals in multiple relation to the main contact members which are so arranged and constructed as to coöperatively engage one another with any predetermined pressure at the instant that their engagement is 60 effected. Moreover, these intermediate contact terminals are adapted to be brought into engagement with a sliding or wiping motion which serves to clean the contact surfaces. Furthermore, the disposition of the intermediate 65 contact terminals and their supporting means is such as to relieve the supporting means from any undue strain or tendency to buckle which might otherwise be caused in case of any slight roughness upon the coöperating 70 contact surfaces of the contact terminals.

Our invention may be best understood by reference to the accompanying drawing, in which—

75 Figure 1 is a view in side elevation of a portion of a circuit interrupter constructed in accordance with our invention, Fig. 2 is a view in front elevation of a portion of the mechanism shown in Fig. 1, the movable carbon terminal and its supporting arm being removed for the sake of clearness. Fig. 3 is a detail view, in side elevation, of the retaining member shown in Figs. 1 and 2, and Figs. 4 and 5 are outline views of the coöperating carbon arcing terminals shown in Figs. 1 and 2, illustrating the positions of the terminals and their associated parts during two successive stages in the opening operation of the interrupter.

90 Referring to the drawing, the device here shown comprises an insulating panel 1, a main stationary contact member 2, a movable coöperating contact member 3, a plurality of carbon arcing terminals 4 and 5 having coöperating contact plates 6 and 7, a supporting linkage 8 for the carbon terminal 4, a supporting arm 9 for the carbon terminal 5, a stationary intermediate terminal 10 and a movable resiliently supported contact terminal 11 to coöperate therewith.

95 The main contact member 2 constitutes a block having an integral stud 12 which projects through the insulating panel 1 and is suitably secured thereto, and the movable contact member 3 is of well-known construction and comprises a plurality of laminae 13 of conducting material which are

assembled in the form of a bridging brush and are suitably secured to a supporting arm 14. The supporting arms 9 and 14 may be pivotally mounted upon portions of the supporting structure (not shown) and may be operatively associated, the one with the other, through the agency of a suitable means embodying lost motion connection, such as is common to this art.

- 10 Inasmuch as our invention pertains directly to the arcing terminals and has no particular relation to the usual operating mechanism of the circuit interrupter and other parts thereof which are essential to 15 the construction of such a device, these parts are not illustrated or described, it being believed that our invention may be well understood without illustration or description of these well-known parts.
- 20 Secured to the main contact member 2 and electrically connected therewith is a supporting bracket 15 having a plurality of upwardly projecting arms 16 between which one or more carbon arcing terminals 4 are 25 mounted. The arcing terminal 4 comprises a block of carbon or other suitable material which is fastened rigidly to a member 17 by means of bolts 18 and 19. The lower front portion of the terminal 4 is recessed and 30 adapted to receive the contact plate 6 which is secured in position by the bolt 19, the outer surface of the contact plate 6 and the carbon terminal 4 being in the same plane. The contact plate 6 is provided with an integral 35 downwardly projecting extension 20 to which one end of a flexible conducting member 21 is attached, the other end of said member being fastened to the main contact member 2 in a manner that will be hereininafter set forth. Thus a path of high 40 electrical conductivity is provided between the main contact member 2 and the tertiary contact plates 6.

The member 17 is provided with projecting side flanges 22, and a flange 23 disposed between them and at right angles thereto. The outer surfaces of the several side flanges 22 are provided with recesses 24 and with holes 25. The recesses 24, just referred to, 50 are adapted to receive the upper ends of supporting links 26 that are pivotally secured to the flanges 22 by means of pins 27, which project through the holes 25. The lower ends of the links 26 are pivotally 55 mounted upon the supporting bracket 15, through the agency of a rod 29 which projects through holes in said links and in the arms 16.

The arms 16 are provided with laterally 60 and inwardly projecting lugs 30 which are adapted to serve as stops for the links 26, and the forward movement of the carbon terminal 4 is also limited by the engagement of the links 26 with the lower portions 31 of the recesses 24. The backward movement

of the links 26 and the contact terminal 4 is arrested by a strap 32 which is secured to the arms 16 and extends the full width of the supporting bracket 15. Thus, the movement of the links 26 and the terminals 4 is confined to prescribed limits, whereby the desired operation is insured. 70

One end of a resilient member 33 rests against the flange 23 of the member 17 and thereby maintains the arcing terminal 4 in engagement with its coöperating contact member 5, as will be readily understood. The other end of the resilient member 33 is attached to a portion 34 of the bracket member 15. A plate 35 is fastened to the front 80 edges of the projecting arms 16 and serves to protect and inclose the flexible conductor 21 and the member 33.

The intermediate auxiliary contact terminal 10 is secured to the main contact 85 member 2 by means of screws 36, and the lower end of the flexible conductor 21 is clamped between said terminal 10 and said contact member 2. Furthermore, the contact terminal 10 is provided with a contact 90 surface 37 that is inclined at a suitable angle to the vertical, for a purpose to be herein-after set forth.

The supporting arm 9 may be of any suitable construction and may be pivotally 95 mounted at its lower end, in a well-known manner, to the main supporting structure (not shown). The movable carbon contact terminal 5 is similar in construction to the contact terminal 4 and is secured to the supporting arm 9 in much the same manner, by means of bolts 18 and 19, it being understood that the terminal 5 is rigidly attached to the supporting arm 9 and is not adapted for rotative movement. The contact plate 7 100 is associated with the contact terminal 5 in a manner similar to that hereinbefore described, and the plate 7 is electrically connected to the movable contact member 3, through the agency of a flexible conducting 110 member 38.

The contact terminal 11, which is adapted to coöperate with the stationary contact terminal 10 is mounted upon the free end of a resilient member 39, the other end of which is rigidly attached to the clamping plate 14. It is essential to the desired operation of the interrupter that the supporting member 39 be disposed in approximately 115 the same plane as the inclined contact surface 37 when the breaker is closed. An adjusting screw 40 is provided intermediate the ends of the resilient member 39 and is adapted to rest against the movable member 3, whereby the resilient member 39 may 120 be maintained under any desired initial tension, so that a considerable pressure is exerted between the coöperating contact terminals 10 and 11 when engagement thereof 125 is effected. 130

Assuming that the various parts of the interrupter occupy the positions shown in Figs. 1 and 2 and that the restraining means (not shown) of the interrupter is released, the operation is as follows: The supporting arm 14 and its associated contact member 3 move outwardly about their pivotal support (not shown), thereby effecting the disengagement of the main contact members 2 and 3, it being understood that, as soon as these members are separated, the current traversing the interrupter parts is carried by the several sets of auxiliary contact terminals. After the separation of the main contact members 2 and 3, the intermediate contact terminals 10 and 11 are disengaged, thereby causing the contact plates 6 and 7 and the coöperating carbon contact terminals 4 and 5 to carry all of the current.

While the separation of the main contact members 2 and 3 and the intermediate contact terminals 10 and 11 is being effected, the entire surface of the carbon contact terminal 4 is maintained in engagement with the coöperating surface of the carbon terminal 5 by means of the spring 33, which acts against the member 17. After contact terminals 10 and 11 have become disengaged, the arm 9, acting through the connecting means (not shown) begins to move outwardly and allows the terminals 4 and 6 to be moved forward by the spring 33. During this operation, the terminals 4 and 5 and 6 and 7 are maintained in full engagement, until the links 26 are rotated about their pivotal support 29, and the movement thereof is arrested by the stops 30. It will, of course, be understood that, on account of the linkage mechanism 8 to which the carbon terminal 4 is secured, said terminal is slightly lowered in position during the first portion of the opening operation, the parts occupying the positions shown in Fig. 4 at a particular moment in the operation. As the supporting arm 9 continues to move outwardly, the carbon terminal 4 is given a rotative movement about its pivotal supports 27, thereby causing said terminal to tilt forward and effect separation of the contact plates 6 and 7. Obviously, after the separation of the plates 6 and 7, all of the current is carried by the carbon terminals 4 and 5, which interpose a progressively increasing resistance as the terminal 4 continues to tilt, thus preventing excessive arcing at the moment of final interruption. The forward rotative movement of the terminal 4 is limited by the engagement of the portions 31 of the recess 24 with the link 26, as already explained.

The structural details and the arrangement and location of parts, as well as the relative proportions thereof, are so chosen that the several sets of contact members and terminals are successively opened and, more-

over, the main contact members 2 and 3 and the auxiliary contact terminals 10 and 11 and 6 and 7 are sufficiently separated, prior to the final disengagement of the carbon terminals 4 and 5, to prevent the formation of an arc between them at the instant of final interruption.

The positions of the various parts are shown in Fig. 5 just prior to the disengagement of the carbon contact terminals 4 and 5. Subsequent to the disengagement, thereof, the movable parts of the interrupter are caused to be moved to their full open positions, as will be readily understood by those skilled in the art.

In closing the interrupter, the supporting arm 9 is moved inwardly, and the circuit is first completed through the carbon contact terminals 4 and 5 in the manner shown in Fig. 5. As the supporting arm 9 continues to be moved inwardly, the carbon contact terminal 4 is first given a rotative movement about its pivotal supports 27, whereby the contact terminals 4 and 5 are caused to engage each other throughout their entire contact surfaces, as shown in Fig. 4. As the closing operation proceeds further, the terminal 4 is forced inwardly against the spring 33, and the links 26 are caused to rotate about their pivotal support 29 until said links are restricted in their movement by reason of their engagement with the member 32. It will be understood that, as the final step in the closing operation is effected, the contact terminal 4 is moved upwardly, whereby a sliding or wiping action is effected between the terminal members 4 and 5. Thus, a good electrical contact is obtained and the contact surfaces are cleaned and maintained in good operating condition.

Prior to the final closure of the interrupter, the intermediate contact terminal 11 is brought into engagement with the inclined surface 37 of the stationary terminal 10 and, by reason of the initial tension in the spring 39, the adjustment of which has hereinbefore been explained, a positive and definite pressure is at once established between the coöperating intermediate terminals 10 and 11. After the initial engagement of the terminals 10 and 11 and during the remainder of the movement of the arm 14 and its associated contact member 3, a sliding or wiping action is produced between said terminals as the terminal 11 is moved upwardly along the inclined contact surface 37 of the terminal 10. As already explained, the resilient supporting member 39 for the terminal 11 is disposed in approximately the same plane as when the breaker is closed, and, consequently, in case the contact surface is rough and defective, by reason of severe arcing, the mechanical resistance to the movement of the terminal 11 is exerted substantially in the plane of the member 39.

and bending and buckling thereof is therefore prevented.

Obviously, the coöperative engagement of the contact terminals 2 and 3 is effected last, 5 after all of the other auxiliary contact terminals have been closed.

Manifestly, many devices embodying the essential elements of our invention, but which differ slightly in structural details

10 and general arrangement of parts, may be constructed within the spirit and scope of our invention, and we desire that only such limitations shall be imposed as are indicated in the appended claims.

15 We claim as our invention:

1. In a circuit interrupter, the combination with relatively movable contact members, of a link for pivotally supporting one of the contact members, and a stop adapted 20 to be engaged on one side by the link to limit its outward movement and adapted to be engaged on its other side by a projection on the contact member to guide and limit its rotational movement.

2. In a circuit interrupter, the combination with relatively movable main and auxiliary contact members, of a doubly-pivoted supporting means for the auxiliary contact member, and a single means for coöperating 30 with the supporting means for limiting its outward movement and for coöperating with the auxiliary contact member for limiting its rotative movement.

3. In a circuit interrupter, the combination with relatively movable main and auxiliary contact members, of a doubly-pivoted supporting means for the auxiliary contact member, and a lug for engaging the supporting means to limit its movement and 40 for engaging the auxiliary contact member to limit its rotative movement.

4. In a circuit interrupter, the combination with relatively movable main and auxiliary contact members, of a doubly-pivoted supporting means for the auxiliary contact member, and a lug for engaging the supporting means to limit its movement and for engaging a projection on the auxiliary contact member to limit its rotative movement. 45

5. In a circuit interrupter, the combination with relatively movable main and auxiliary contact members, of a pair of links for pivotally supporting the auxiliary contact member on a common axis, resilient means 50 for maintaining the auxiliary contact members in engagement when the interrupter is closed, and two lugs, the auxiliary contact members being adapted to engage the lugs on one side and the links being adapted to 55 engage the lugs on their other sides to limit the relative outward and rotative movements thereof, respectively.

6. In a circuit interrupter, the combination with relatively movable contact members, of a link for pivotally supporting one of the contact members, a spring for maintaining the contact members in engagement when the circuit interrupter is closed, and a single means adapted to be engaged on one 65 side by the contact member and on the other side by the link to limit the relative outward and rotative movements thereof, respectively.

In testimony whereof, we have hereunto 75 subscribed our names this 25th day of Sept., 1912.

JOSEPH N. MAHONEY.
WALTER M. AUSTIN.
